GRID-CONTROLLED IGNITOR FOR
IGNITRONSMarshall Middleton, Jr., Pittsburgh, Pa., assignor
to Westinghouse Electric Corporation, East
Pittsburgh, Pa., a corporation of Pennsylvania

Application June 14, 1952, Serial No. 293,611

18 Claims. (Cl. 313—167)

1

My invention relates to ignitrons, which may be defined as single-anode pool-type vapor-arc asymmetrically conducting tubes. In the broader aspects of my invention, any suitable vaporizable reconstructing cathode-metal may be used, including any one of a number of known metals for this purpose, the list including mercury, cadmium, cesium, rubidium, potassium, and perhaps other metals.

The general object of my invention is to provide an insulated grid which is disposed closely around the ignitor or starting-electrode of such a tube, in such position as to control the electrostatic field or voltage-gradient near the surface of the ignitor or starting-electrode. An advantage of this kind of arrangement of grid is among other things, that it can be used to control the instant at which a cathode-spot is initiated by the ignitor or starting-electrode, without interposing any impediment in the main space-current discharge-path through which arcs may play between the whole remainder of the cathode pool-surface and the main anode of the device.

The special ignitor-enclosing grid may also have an important function in guarding the ignitor or starting-electrode against the restriction of an arc thereto after the initial ignitor-arc has been transferred to cathode-spots in other portions of the pool-surface of the cathode, because my special grid, which is confined to the region immediately surrounding the ignitor or starting-electrode, is or may be able to exert an important measure of control over the electrostatic field or voltage-gradient in the vicinity of the ignitor or starting-electrode, even while the tube is conducting heavy currents by means of arcs which terminate at cathode-spots on portions of the cathode-pool which are removed from the immediate vicinity of the ignitor or starting-electrode, this field-controlling grid-operation being possible as soon as the initial ignitor-generated cathode-spot has been transferred to some more remote portion of the pool-surface.

My invention was initially designed for the protection or control of a hot-cathode type of filamentary starting-electrode which was designed by John L. Boyer for use in alkali-metal ignitrons, as described in an application, Serial No. 293,594, filed June 14, 1952, for Thermionic Ignitors for Alkali-Metal Ignitrons. In this alkali-metal igniton, the vaporizable reconstructing cathode-material was chosen from the alkali-metal list consisting of cesium, rubidium

2

and potassium, with special emphasis on cesium as being perhaps the most desirable alkali-metal cathode-material, so far as now appears. The broad conceptions of the use of one of these alkali metals are set forth in a Boyer and Colaiaco application, Serial No. 144,354, filed February 15, 1950, and the broad conceptions relative to a cathode-pool type of tube, using such an alkali metal, are set forth in a Boyer application, Serial No. 206,434, filed January 17, 1951, and these broad conceptions need not be repeated in great detail in the present description. As explained in the first paragraph of said Boyer and Colaiaco application, these three alkali-metals, cesium, rubidium and potassium, form a more or less distinctive class by themselves, which may be described as the alkali-metals having four, five and six shells in their atomic structures, or the stable alkali-metals having more than three shells in their atomic structures.

These heated-filament ignitors or make-alive electrodes of pool-type alkali-metal single-anode tubes are unique, among ignitors, because they run hot all the time, and hence, in the absence of some grid-control means, they can not be prevented from firing the tube, or initiating an arc, as soon as the tube-anode becomes positive with respect to the cathode. This is a disadvantage, as compared to the semiconducting type of cool-running ignitors which are useful in mercury-arc ignitrons, because the necessary starting-impulse can be applied to the cool-running semiconductor ignitors at any chosen delayed time after the commencement of the positive wave-portion of the anode, thus obtaining the advantage of controlled delayed firing. My individual grid-control, around a hot-cathode or thermionic starting-element for an alkali-metal igniton, provides a means for preventing the hot-cathode starting-element from forming a cathode-spot until the correct space-gradient conditions are permitted by the potential-control exerted by the grid. In this respect, the hot-cathode ignitor for an alkali-metal igniton differs from the ordinary cool-running semiconductor ignitor for a mercury-arc igniton, because the cool-running semi-conducting mercury-immersed ignitor forms a heated cathode-spot whenever it receives its adequate current-impulse, regardless of the status of the space-current field in its vicinity.

With the foregoing and other objects in view, my invention consists in the circuits, systems, apparatus, combinations, parts, and methods of

design and operation, which are hereinafter described with reference to the accompanying drawing, wherein the single figure is a much simplified and somewhat diagrammatically indicated view of circuits and apparatus showing an exemplary form of construction of the tube itself, and an exemplary form of external circuits which may be employed in the use of the tube.

In the exemplary form of my invention shown in the drawing, I show an asymmetrically conducting vapor-arc device comprising an evacuated container 1, having two, and only two, main electrodes therein, namely a main anode 2 and a pool-type cathode 3. The container 1 is illustrated as being made of an insulating material such as glass. The main anode 2 is illustrated as a thin-walled cup-shaped member 4, the open top end of which is sealed into an opening in the top of the glass container 1. An anode-terminal 5 extends up from the bottom of the anode-cup 4.

The cathode-pool 3 is contained in the bottom of the glass container 1, and it is provided with a cathode-terminal 6 which extends down through a press 7 in the bottom of the container. The pool-type cathode 3 may be either an open pool or a sponge-held pool in which a porous substantially non-vaporizable material holds at least the active portion of the vaporizable reconstructing cathode-material. The vaporizable reconstructing cathode-material may, in the broadest applications of my invention, be any of the metals which are known to be utilizable for that purpose, including mercury, cadmium and the three heavier stable light metals of the alkali-metal group comprising cesium, rubidium and potassium, although, as previously intimated, my invention is of particular significance as applied to an alkali-metal ignitron or single-anode asymmetrically conductive vapor-arc device, in which the active part of the vaporizable reconstructing cathode-material is selected from the group consisting of cesium, rubidium and potassium. When the vaporizable reconstructing material of the cathode-pool is cesium, or a mixture of metals containing cesium or one of the other metals of the alkali-metal group consisting of cesium, rubidium and potassium, the internal voltage-drop in the tube is usually less than half of that which is obtained in a mercury-pool tube of corresponding design, which means a greater efficiency.

The evacuated tube also contains an auxiliary starting-electrode 8, the operating portion of which is an elongated member or filament 9 which is suitable for use as a hot-cathode element of a limited surface-area. One end of the filament 9 is immersed in the cathode pool 3, and is shown as being extended down into engagement with the top end of the cathode-terminal 6. The unimmersed end of the filament 9 is secured to, and supported by, the inner end of a stiff ignitor-terminal 10, which extends out through a press 11 in the side of the container 1.

In accordance with my present invention, an insulated grid 13 is disposed closely around the hot-cathode starting-electrode or filament 9, and usually also around the inner end of the ignitor-terminal 10, in position to control the voltage-gradient thereof prior to an initiation of an arc in the device. Preferably, as shown, this insulating filament-controlling grid 13 is of a substantially tubular construction, and if the filament 9 is bent, as is shown in the illustrated form of embodiment of my invention, then the

tubular grid 13 is also correspondingly bent, as shown in the drawing. This insulated grid-member 13 is suitably supported, so that it is out of contact with either the starting-electrode 8 or the cathode. As shown, it is supported by means of a stiff supporting-wire 14 which is secured to the inner end of a stiff grid-terminal 15 which extends out of the side of the tube through a press 16.

In the broader aspects of my invention, the filamentary or hot-cathode type of starting-electrode or ignitor 8 is to be regarded as being representative of any suitable ignitor or starting-electrode, including the well-known cool-running semiconducting make-alive devices which have had such successful use, when dipping down into a pool of mercury, in which case my pool-type cathode 3 would be a mercury pool, and the starting-electrode would ordinarily merely dip down into the pool, without being fastened to the cathode-terminal 6. My ignitor-encircling grid 13 would therefore act as a means whereby some control could be exerted over the initial firing of the tube at the beginning of each conducting period thereof. It is also quite likely that such an ignitron-enclosing grid will have a desirable utility as a means for preventing the restriking of the arc, against the ignitor or starting-electrode, at any later time during the conducting period of the tube. If the lower end of the tubular grid 13 comes in close enough spacing to the surface of the pool 3 (as compared to the radius of the tubular grid 13), then the tubular grid might very probably be used as a means for preventing the striking of an arc between the main anode 2 and the point of immersion of the starting electrode with the cathode-pool, even though the starting electrode is of the cold-operating immersed semiconductor type which is capable of producing a cathode-spot at its point of immersion, regardless of the nature of the electrostatic field surrounding it.

My invention was particularly designed for, and is of particular significance as applied to, a cesium ignitron, or other alkali-metal ignitron, in which the active vaporizable reconstructing cathode-material is either cesium, rubidium or potassium. In such a case, the active part of the starting-electrode 8 must be a heated filament 9, but the filament is not ordinarily heated to incandescence, as is necessary in the case of ordinary filamentary cathodes which do not operate in the presence of the vapor of cesium, rubidium or potassium. As applied to a cesium tube, or other alkali-metal tube, the filamentary starting-electrode or ignitor 9 has to be made of a material having a work-function which is higher than the ionization potential of the active vaporizable cathode-metal. When this is so, a supposedly monatomic film of the vaporizable cathode-metal is formed on the surface of the heated filament, thus causing the filament to have a low-energy electron-emission, due to the presence of the vaporizable cathode-metal, at emitting temperatures which are materially below the thermionic emitting temperature of the filament-metal alone, without the film of the cathode-metal thereon. Of course, all that is necessary, is that the surface-portion of the filament shall be of the proper metallic construction, having a sufficiently large work-function as just described, but ordinarily it is more convenient to make the entire filament of the desired metal.

Such hot-cathode members of alkali-metal tubes distinguish from incandescent thermionic

emitters in having a much lower electron-density per unit area, so that there is much less likelihood of forming a cathode-spot on the surface of the heated element, unless there is an adequate potential-gradient in the space-charge immediately surrounding the heated surface. In this way, a low-area heated-cathode element, such as my filament 9, in an alkali-metal tube, is readily susceptible of being controlled, as to the time of initiation of an arc therein, by means of a closely spaced grid 13, and therein lies the particular applicability of my present invention to this particular type of device.

After a cathode-spot has been formed, by the operation of the filamentary starting-electrode 9, an arc or arcs will spread out randomly over the cathode-pool surface (if the load-current demand is large enough), and it is desirable to prevent an arc from the main anode 2 from fastening on any portion of the tubular grid-member 13. Since this tubular grid member 13 is now operating within the internal space which is intensely heated by the play of the arc or arcs, such grid will be running quite hot, and it is quite desirable that it should not become a hot-cathode electron-emitter, like the filamentary starting-electrode 9. To this end, it is quite desirable that the tubular grid 13, and any other non-emitting hot-running metal parts, such as the grid-supporting wire 14, and usually at least the inner end of the ignitor-terminal 10, shall be made of a metal, or at least shall have a surface which is composed of a metal, having a work-function which is lower than the ionization potential of the particular vaporizable cathode-metal which is being used in the tube. In this way, a thin monatomic filament of the vaporizable cathode-metal does not form on the heated surfaces of these parts which are intended to be non-emitters, as further explained in the previously mentioned Boyer-Colaiaco application.

In the attached table, I have indicated the work-functions of the available high-melting point low-vapor pressure metals as compared to the ionization potentials of cesium, rubidium and potassium.

Work-functions of high-melting-point low-pressure metals, as compared to the ionization potentials of cesium, rubidium and potassium

Metal	Work-Function in Electron Volts	Ionization Potential in Volts
platinum	Pt	5.29
rhenium	Re	5.1
nickel	Ni	4.84
palladium	Pd	4.82
rhodium	Rh	4.65
iridium	Ir	4.57
osmium	Os	4.55
ruthenium	Ru	4.52
tungsten	W	4.50
iron	Fe	4.36
potassium	K	4.32
molybdenum	Mo	4.27
cobalt	Co	4.18
rubidium	Rb	4.16
tantalum	Ta	4.12
vanadium	V	4.11
titanium	Ti	4.09
columbium	Cb	3.99
cesium	Co	3.88
zirconium	Zr	3.84
hafnium	Hf	3.53
thorium	Th	3.41
beryllium	Be	3.37

In the drawing, I have shown exemplary external circuits which illustrate one mode of application or use of my improved tube. In the

particular circuit-illustration which is shown, a polyphase supply-line 21 is used to energize a delta-star-connected main transformer 22, which has, for example, three secondary terminals S1, S2 and S3, one of which is used to energize the anode-terminal 5 of one of my tubes. It will be understood that the other two secondary terminals will be connected to two other tubes which are not shown in the drawing. The secondary star-point is connected to the negative lead or return-conductor L2 of the direct-current load-circuit. The cathode-terminals 6 of all of the tubes are connected to the positive or outgoing lead L1 of the direct-current-load circuit. Between the cathode-terminal 6 and the grid-terminal 15 is a grid-controlling circuit which comprises a grid-resistance 23, a negative grid-biasing means such as a battery B, and the secondary winding 24 of a peaking-transformer 25, the primary of which is energized from one of the secondary phases of a grid-control transformer 26, which is a delta-Y-connected transformer, the primary of which is energized from the polyphase supply-circuit 21 through a phase-shifter 27.

When a filamentary starting-electrode 9 is used, as shown in the drawing, a suitable low-voltage source of filament-heating current must be provided, as described more particularly in the previously-mentioned Boyer application, Serial No. 293,594. This filament-heating source is illustrated in the form of a filament-heating transformer 28, which is shown as being energized from one of the phases of the polyphase supply-circuit 21.

In the preferred form of embodiment of my invention, when the cathode-metal is one of the three alkali metals, for example, cesium, the filamentary starting-electrode 9 is kept, at all times, at a temperature which is above the boiling-point of the particular alkali metal which is being used for the cathode, and usually the operating-temperature of the filament is considerably below the incandescent temperature which is needed for a filament which does not operate in the vapor of the alkali-metal. Further details of the filament-operation are set forth in the previously-mentioned Boyer application, Serial No. 293,594. It will suffice to say, here, that the filament 9 runs hot all of the time when the rectifier-tube is in operation, that is, during the non-conducting periods of the tube as well as during the conducting periods thereof.

At all times when the anode-terminal 5 is positive with respect to the cathode-terminal 6, the biasing-means B keeps the grid-terminal 15 at a potential which is negative with respect to the cathode-terminal 6, except at one brief moment at the beginning of each positive half-cycle of the corresponding secondary-phase of the grid-controlling transformer 26, at which time the peaking-transformer 25 produces a brief positive voltage-impulse in its secondary winding 24, causing the grid-terminal 15 to briefly become positive with respect to the cathode-terminal 6. The adjustment of the phase-shifter 27 is such that the grid-terminal 15 is made positive at a chosen moment or time-phase after the anode-terminal 5 first becomes positive with respect to the cathode-terminal 6.

Before the grid-terminal 15 is made positive, the negative potential of the grid 13 so controls the electrostatic field-distribution within the enclosed space of the tube, that the heated filament 9 can not emit enough electrons to initiate an

arc within the tube. As soon, however, as the grid 13 becomes positive with respect to the cathode-pool 3, assuming that the main anode 2 is also positive with respect to the cathode 3, the heated filament 9 starts a copious emission of electrons, which lasts for a brief instant, during which time the adhering monatomic film of the alkali metal is rapidly evaporated or dissipated from the limited surface-area of the filament, by reason of the fact that the total space-current electron-emitting capacity of the filament is small compared to the normal current-demands of the direct-current load-circuit L-1, L-2.

In the very brief time, however, during which the filament is carrying the load-current of the tube, it forms a cathode-spot on the filament, which presumably creeps down, practically instantaneously, toward the immersed end of the filament, which is cooled by the cathode-pool, and the arc thereupon transfers itself to the cathode-pool 3. If the direct-current load is great enough, it will be necessary for the cathode-pool 3 to form other cathode-spots, which have a tendency to spread out randomly over the surface of the cathode-pool, at points which are more favorably situated, with respect to the anode 2, than the filament-immersion point which is under the lower end of the tubular grid 13.

If this tubular grid 13 is driven to a sufficiently negative potential, after the brief duration of the positive voltage-impulse of the peaking-transformer 25, the arc-drop from the main anode 2 to the immersion-point of the filament 9 can be increased, thus assisting in extinguishing the cathode-spot or cathodic arc-terminal at said junction point, in favor of more favorably located cathode-spots elsewhere on the surface of the cathode-pool 3. At any rate, once the cathode-spot at said immersion-point is extinguished (having been transferred to some other cathode-spot elsewhere on the cathode-pool), a negative potential on the filament-enclosing grid 13 will very probably suffice to control the electrostatic field within the relatively small space underneath the tubular grid-member 13, thus preventing a re-striking of the arc at the immersion-point of the filament and also protecting the filament against its carrying any arc.

It will be noted that the provision of a grid which is individual to the elongated immersed starting-electrode 9, which it closely surrounds, provides a construction in which the main arc-ing-space between the anode 2 and all the rest of the cathode pool 3 is free of any arcing-impediment, such as would be caused by a grid which extended all the way across this main arc-ing-space. Hence, the internal voltage-drop in my tube is not increased by the presence of the grid 13, because said grid is limited to a space which closely surrounds the starting-electrode 9 and the inner end of the electrode-terminal 10.

Similar grid-controlling effects are obtained in the event that the cathode-metal is some metal other than one of the three alkali metals, as has already been pointed out, the essential (and important) difference being that the moderate emitting-temperature of a heated-filament is lost, if the vapor is not the vapor of one of the alkali metals, as already pointed out.

While I have described my invention, and illustrated it, in but a single illustrative form of tube-structure, and with only one illustrative form of external circuit-connections therefor, and while I have greatly simplified my illustrations, omitting such details as switch-means,

cooling-means, temperature-controls, shields, and numerous other features which are known to the skilled workers of the art, I wish it to be understood that my invention is susceptible of modification in all of these respects, and in many other respects involving the substitution of equivalents and the addition or omission of various parts.

I claim as my invention:

1. An asymmetrically conducting vapor-arc device comprising an evacuated container having two, and only two, main electrodes therein and also having an auxiliary starting-electrode therein, the operating portion of one of the main electrodes being a pool-type cathode including a vaporizable reconstructing cathode-material, the operating portion of the other one of the main electrodes including an active face-portion comprising the active main anode of the device, and the operating portion of the starting-electrode being an elongated member having one end immersed in said pool-type cathode, and an insulated grid disposed closely around the starting-electrode in position to control the voltage-gradient near the surface thereof prior to the initiation of an arc in the device.

2. The invention as defined in claim 1, characterized by the grid being of a substantially tubular construction.

3. An asymmetrically conducting vapor-arc device comprising an evacuated container having two, and only two, main electrodes therein and also having an auxiliary starting-electrode therein, the operating portion of one of the main electrodes being a pool-type cathode including a vaporizable reconstructing cathode-material an active part of which is selected from the group consisting of cesium, rubidium and potassium, the operating portion of the other one of the main electrodes including an active face-portion comprising the active main anode of the device, and the operating portion of the starting-electrode being an elongated member suitable for use as a hot-cathode element of limited surface-area having one end immersed in said pool-type cathode, said hot-cathode element having a surface of a metal having a work-function which is higher than the ionization potential of the active vaporizable reconstructing cathode-material, and an insulated grid disposed closely around the starting-electrode in position to control the voltage-gradient near the surface of the hot-cathode element prior to the initiation of an arc in the device.

4. The invention as defined in claim 3, characterized by the grid being of a substantially tubular construction.

5. The invention as defined in claim 3, characterized by the grid having a surface-metal having a work-function which is lower than the ionization potential of the active vaporizable reconstructing cathode-material.

6. The invention as defined in claim 5, characterized by the grid being of a substantially tubular construction.

7. An asymmetrically conducting vapor-arc device comprising an evacuated container having two, and only two, main electrodes therein and also having an auxiliary starting-electrode therein, the operating portion of one of the main electrodes being a pool-type cathode including a vaporizable reconstructing cathode-material an active part of which is selected from the group consisting of cesium, rubidium and potassium, the operating portion of the other one of the main electrodes including an active face-portion com-

prising the active main anode of the device, and the operating portion of the starting-electrode being an elongated member suitable for use as a hot-cathode element of limited surface-area having one end immersed in said pool-type cathode, said hot-cathode element having a surface of a metal having a work-function which is sufficiently high, as compared to the ionization potential of the active vaporizable reconstructing cathode-material, so as to cause said hot-cathode element to have a low-energy electron-emission due to the presence of the active cathode-material at emitting-temperatures materially below the thermionic emitting-temperature of the hot cathode surface-metal alone, without the active vaporizable reconstructing cathode-material, and an insulated grid disposed closely around the starting-electrode in position to control the voltage-gradient near the surface of the hot-cathode element prior to the initiation of an arc in the device.

8. The invention as defined in claim 7, characterized by the grid being of a substantially tubular construction.

9. The invention as defined in claim 7, characterized by the grid having a surface-metal having a work-function which is sufficiently low, as compared to the ionization potential of the active vaporizable reconstructing cathode-material, so as to substantially prevent electron-emitting surface-absorption of the active vaporizable reconstructing cathode-material on said grid.

10. The invention as defined in claim 9, characterized by the grid being of a substantially tubular construction.

11. An asymmetrically conducting vapor-arc device comprising an evacuated container having two, and only two, main electrodes therein and also having an auxiliary starting-electrode therein, the operating portion of one of the main electrodes being a pool-type cathode including a vaporizable reconstructing cathode-material an active part of which is a stable alkali-metal having more than three shells in its atomic structure, the operating portion of the other one of the main electrodes including an active face-portion comprising the active main anode of the device, and the operating portion of the starting-electrode being an elongated member suitable for use as a hot-cathode element of limited surface-area having one end immersed in said pool-type cathode, said hot-cathode element having a surface of a metal having a work-function which is higher than the ionization potential of the active vaporizable reconstructing cathode-material, and an insulated grid disposed closely around the starting-electrode in position to control the voltage-gradient near the surface of the hot-cathode element prior to the initiation of an arc in the device.

12. The invention as defined in claim 11, characterized by the grid being of a substantially tubular construction.

13. The invention as defined in claim 11, characterized by the grid having a surface-metal having a work-function which is lower than the ionization potential of the active vaporizable reconstructing cathode-material.

14. The invention as defined in claim 13, characterized by the grid being of a substantially tubular construction.

15. An asymmetrically conducting vapor-arc device comprising an evacuated container having two, and only two, main electrodes therein and also having an auxiliary starting-electrode therein, the operating portion of one of the main electrodes being a pool-type cathode including a vaporizable reconstructing cathode-material an active part of which is a stable alkali-metal having more than three shells in its atomic structure, the operating portion of the other one of the main electrodes including an active face-portion comprising the active main anode of the device, and the operating portion of the starting-electrode being an elongated member suitable for use as a hot-cathode element of limited surface-area having one end immersed in said pool-type cathode, said hot-cathode element having a surface of a metal having a work-function which is sufficiently high, as compared to the ionization potential of the active vaporizable reconstructing cathode-material, so as to cause said hot-cathode element to have a low-energy electron-emission due to the presence of the active cathode-material at emitting-temperatures materially below the thermionic emitting-temperature of the hot cathode surface-metal alone, without the active vaporizable reconstructing cathode-material, and an insulated grid disposed closely around the starting-electrode in position to control the voltage-gradient near the surface of the hot-cathode element prior to the initiation of an arc in the device.

16. The invention as defined in claim 15, characterized by the grid being of a substantially tubular construction.

17. The invention as defined in claim 15, characterized by the grid having a surface-metal having a work-function which is sufficiently low, as compared to the ionization potential of the active vaporizable reconstructing cathode-material, so as to substantially prevent electron-emitting surface-absorption of the active vaporizable reconstructing cathode-material on said grid.

18. The invention as defined in claim 17, characterized by the grid being of a substantially tubular construction.
